ABSTRACT OF THE DISCLOSURE

A control valve for regulating the flow of fluid between a fluid source and a cylinder containing a fluid actuated piston. The valve includes a flow control mechanism to cushion the initial high pressure loads resulting from extreme forces applied to the piston at the beginning of a work stroke and a hydraulically actuated combination check and delay valve assembly to delay the return of the piston to the extended position after the work stroke.

The present invention relates to a control mechanism for presses and the like and more particularly to a simplified and improved cushioning and delaying hydraulic control system for controlling the movement of a die pad to and from a working position in a press.

In modern, high speed presses commonly utilized for performing stamping, drawing or other operations upon sheet metal, it is necessary to provide for accurate, controlled movement of the die pad normally carrying the lower of the cooperating die elements of the press. The die pad conventionally contacts at least one cylinder contained piston and is movable with the piston. It has been previously proposed, for example, by U.S. Reissue Patent No. 25,027 and like developments, to provide a hydraulic system for controlled die pad movement consisting of an accumulator and cylinder connected by a normally closed check and shutoff valve block and utilizing a separate normally closed by-pass relief valve block in parallel with the check and shutoff valve block. By this arrangement, two separate costly controlled hydraulic flow path mechanisms are necessitated, flow from the cylinder to the accumulator being prohibited through the normally closed check and shutoff valve block, and flow from the accumulator to the cylinder being prohibited through the normally closed by-pass relief valve block.

In such systems, the shutoff valve delays return of the piston to its extended position, to aid in stripping parts from the die elements. Thus, accumulator-to-cylinder flow must be completely prevented which, of course, necessitates complete closure of the relief valve during that interval. Thereafter, the piston assumes its extended position, followed by actuation of the press to its closed or working position. Subsequently, the piston is forced downward within the cylinder by the press work stroke to subject hydraulic fluid trapped underneath the piston to an initial pressure proportional to the working pressure of the press.

Initial downward movement of the piston is firmly resisted by the unvented hydraulic fluid trapped between the cylinder and the normally closed relief valve before the relief valve opens for venting of the fluid to permit downward displacement of the die pad. High contact pressures are generated between the die elements and within the hydraulic system during this initial unvented interval, thereby inducing a substantial shock load upon the entire press and hydraulic system. This decreases the useful life of the apparatus and increases the cost of maintaining it.

Upon opening of the press, pressure differential within the hydraulic system causes fluid to return to the cylinder

2

through the by-pass relief valve to reposition the piston along with the die pad in the elevated position preparatory for the next working stroke of the press.

The present invention overcomes or substantially alleviates the above-recited prior art disadvantages by providing an improved hydraulic control system which has a continuously open variable discharge relief valve in combination with a hydraulically floating combination check and delay valve assembly for cushioning the initial closing and subsequent downward movement of the die elements by accommodating controlled hydraulic fluid flow from the cylinder to the accumulator through the continuously open relief valve and a variable volume reservoir during that interval of the press operation.

The present invention is easy of initial installation, incurs comparatively low maintenance costs, is simplified in construction and is adaptable to a wide variety of workpieces whereby any set of a series of die elements may be utilized.

It is, therefore, a primary object of the present invention to provide a novel control valve assembly for controlling movement of the die pad to and from a working position in a press.

Another object of this invention is the provision of a novel improved and substantially simplified valve assembly having a flow control valve mechanism such as to cushion initial contact of the die elements and the resulting shock load upon the hydraulic system, thereby alleviating the extremely high initial hydraulic pressure loads encountered at the beginning of each press work stroke. The flow control valve mechanism is preferably of unitary construction allowing for easy, unitary removal and replacement according to maintenance requirements.

A further object of the present invention is to provide a novel hydraulically floating combination delay and check valve assembly, hydraulically actuated and providing a common main passage in the valve body for flow to and from the cylinder and having means for delaying return of the piston to the extended position after the press work stroke.

Yet another, and no less important, object is to provide a novel variable volume reservoir within a main valve body for cushioning initial contact of the die element and hydraulic shock pressure loads at the commencement of the press work load and for delaying return of the piston to its extended position.

Other objects of this invention will become apparent from the following description and appended claims, in conjunction with the accompanying drawings, wherein:

FIGURE 1 is a schematic representation of a die pad press control mechanism, especially illustrating in detail a presently preferred hydraulic control valve assembly of the present invention in a neutral or inactive position;

FIGURE 2 is a fragmentary schematic of the mechanism of FIGURE 1 with the control valve assembly positioned for cylinder-to-accumulator flow; and

FIGURE 3 is another fragmentary schematic of the mechanism of FIGURE 1 with the control valve assembly positioned for accumulator-to-cylinder flow.

GENERAL DESCRIPTION

As shown in FIGURE 1, it will be seen that an accumulator 10 supplies hydraulic fluid to hydraulic line 11 at standard shop air pressure, for example, on the order of 80 to 100 p.s.i., to main valve body 12, thereafter through hydraulic line 13 into cylinder 14, the hydraulic fluid entering beneath die supporting piston 15.

The hydraulic fluid in cylinder 14 beneath the piston 15 provides a cushion to protect the die as the press ram descends. A time delay in returning piston 15 to its extended position following the work stroke is achieved

by a novel assembly within valve body 12 which temporarily prohibits return of hydraulic fluid to cylinder 14 for the period of delay desired. This time delay is integrated with the press operation to aid in stripping pressed workpieces from the die elements. Once the delay has been achieved, valve body 12 accommodates full flow of hydraulic fluid from accumulator 10 to cylinder 14, thereby restoring piston 15 to its elevated position.

Specifically, with reference to the drawing, line 11 supplied fluid to chamber 16 of valve body 12 which is aligned with and opens into cylindrical main valve body bore 17. Additionally, hydraulic line 11 supplies fluid to passageways 18, 19 and 20 of valve body 12, passage 20 communicating with the medial portion of bore 17.

Another flow path providing fluid communication between line 11 and bore 17 is achieved through passages 21 and 22. Retained within passage 21 in stationary position is a cylindrical bleed sleeve 23 which receives therethrough an elongated bleed valve 24. Fluid communication between line 11 and passage 22 through passage 21 occurs through an inclined radial slot 25 of bleed valve 24. Valve 24 is threadedly selectively adjustable by exterior handle mechanism 26 to position slot 25 for selectively varying the small amounts of pressurized fluid discharged from bore 17 to line 11. Since flow can occur through only that portion of the slot 25 exposed beyond the sleeve 23, adjustment of the slot 25 axially in the sleeve 23 adjusts the volume flow.

Main body valve bore 17 receives fixed valve sleeve 27 therein, the interface between bore 17 and the sleeve 27 being sealed by suitable means, as by appropriately sized and spaced O-rings (not shown). Sleeve 27 has a central bore 28 interrupted by radial passage 29 and annular chamber 30a which establishes communication between the sleeve bore 28 and an upper valve block passage 30. A second radial passage 31 is also provided in sleeve 27, together with annular chamber 32, passage 31 and chamber 32 being in constant communication with passage 20. Positioned within the sleeve 27 is a reciprocating valve body 34 having main axial flow passage or recess 35 through which fluid flow to and from cylinder 14 must pass. Valve body 34 also provides rearward radial passages 36 and forward radial passages 37 for fluid communication with passage 35. Radially enlarged piston 38 is carried by and reciprocates with valve body 34 at its forward end, piston 38 being sealed in chamber 16 by means of flexible diaphragm 39 of standard commercial type, the diaphragm 39 engaging the valve block and the piston 38, respectively. Valve body 34 is moved between extreme left and right positions solely by differential fluid pressure acting thereon as explained hereinafter, no compression springs or other external actuating means being required.

Interposed between movable body 34 and piston 38 is annular insert 40 which provides a peripheral valve seat for centrally confined check valve 41. Insert 40 moves unitarily with the reciprocating combination of piston 38 and body 34. Check valve 41 is positioned adjacent the radial flow passage 37 and is urged to its illustrated inactive closed position by compression spring 42.

As illustrated, bore 17 communicates through passage 44 in the upper valve block with a continuously open, variable discharge relief valve assembly 46, passage 44 being located at the lefthand end of sleeve 27. Relief valve assembly 46 is interposed between and provides fluid communication to passage 44 from passage 48, which communicates with cylinder hydraulic line 13, with upper valve block passage 30 and with pressure gauge 50 through passage 52 and bore 54.

Referring now to the details of relief valve 46, which is preferably a unitary cartridge, there is provided stationary outer sleeve 56 radially apertured at 58 into annular chamber 59 to define a stationary pervious portion of the relief valve 46. Chamber 59 facilitates constant open communication between passages 48 and 44. Recipro-

cable valve body or movable portion 60 of relief valve 46 is axially slidably positioned in bore 62 of sleeve 56 and has a chamfered annular edge 63. Lip 64 of valve body 60 is urged against shoulder 66 of stationary sleeve 56 by compression spring 68 so as to leave apertures 58 at least partially open at all times. Orifice 70 vents fluid from conduit 48 through valve body 60 to ball check valve 72 which is normally urged to the closed position by compression spring 74. Check valve 72, when opened, relieves the pressure on the lefthand side of valve body 60 to accommodate leftward sliding thereof to permit greater discharge through apertures 58, thereby cushioning against excessive shock pressure build-up in the hydraulic system. The pressure at which check valve 72 will open is determined by the compression of spring 74 which, in turn, is controlled by selectively settable handle 76.

Interposed between handle 76 and unitary cartridge relief valve 46 is support sleeve 77, attached to the valve body at 79 and to handle 76 at 81, as, for example, by threaded connection. This interrelation of parts provides a significant advantage. When relief valve 46 becomes ineffective due to wear or is in need of service, support sleeve 77 may be conveniently detached from the valve body at connection 79 followed by unitary removal and replacement of the cartridge constituting relief valve 46. Performance of this procedure requires only a few seconds of time and, hence, avoids costly equipment down time.

Disposed in passage 44 between relief valve 46 and bore 17 is check valve 80 which accommodates selective fluid flow from passage 48 into chamber 90 and prevents reverse flow from chamber 90 into passage 48. Check valve 80 is housed in sleeve-like seat 86 and urged to its closed position by compression spring 84. Flow through valve 80 occurs through radial ports 85 and central bore 87 when spring 84 is compressed due to cylinder pressure from passage 48.

OPERATION

40 In the at rest position, as shown in FIGURE 1 immediately preceding the work stroke of the press ram, relief valve 46 is in its idle partially opened position, check valve 80 is closed, being seated against sleeve 86, and the combination of movable body 34, piston 38 and insert 40 is in the extreme rightwardmost position. Consequently, passage 30 is in communication with recess 35 of movable body 34 through radial ports 36. Flow through recess 35 is prevented, since no outlet ports therefrom are open in this position.

50 During the work stroke of the piston 15, cylinder-to-accumulator hydraulic flow results, the pressure in line 13 being significantly greater than the pressure of hydraulic fluid within accumulator 10 and line 11. At the making of initial contact between the die elements, the hydraulic fluid in cylinder 14 and line 13 is instantaneously subjected to a relatively high pressure which is exerted upon the relief valve assembly by passage 48. The shock of this initial hydraulic pressure is initially alleviated by immediate flow of the pressurized fluid through continuously open apertures 58 of relief valve 46.

60 If the apertures 58 were closed, the initial shock could be dissipated only after fluid flow through the aperture 58 and the actuation of the valve element 72 to allow movement of the valve body 60. Thus, the displacement of valve body 60 would require a period of time during which, in effect, a solid column of hydraulic fluid supports the piston 15 and transmits the press shock. However, since the pressure relief valve body 60 need not be displaced by the high hydraulic pressures from line 13 for flow therethrough to occur, an initial small quantity of fluid under cylinder pressure flows through apertures 58, displacing check valve 80 from its seat and accommodating flow through valve 80 and passage 44 into bore 17 to thereby cushion the initial shock of the dies, aid materially in prolonging the useful life of the

press assembly, and provide a significantly improved, i.e., smoother, press operation.

At and immediately following initial contact of the die elements, the press ram forces the piston 15 downwardly, further increasing the pressure in line 13 and passage 48. This pressured fluid flows through orifice 70 to lift ball 72 from its seat, allowing relief valve body 60 to move to the left against the force of spring 68 to increase discharge of fluid through ports 58 and passage 44 into bore 17.

Under cylinder pressure, fluid initially passing through the passage 44 into bore 17 accumulates in the variable volume annular reservoir or chamber 90, thereby exerting pressure upon the righthand face of the piston 38 to unitarily drive piston 38, insert 40 and movable valve body 34 leftward, as viewed in FIGURE 1. This causes movable body 34 to unseat from the fixed sleeve 27 at 92, permitting fluid to flow from the reservoir 90 through passages 37 into the axial recess 35. Reservoir 90 is progressively enlarged as more fluid under cylinder pressure is received through passage 44, while movable body 34, piston 38 and insert 40 continue to move leftward. By this progressively enlarging storage capacity for hydraulic fluid in reservoir 90, excessive cylinder pressure buildup is further alleviated.

While the size of reservoir 90 is progressively enlarging, fluid stored in reservoir 90, recess 35 and valve passage 22 is vented through bleed-valve slot 25 to provide a controlled small discharge into line 11, according to the setting of bleed-valve handle 26, thereby regulating the initial rate of downward movement of piston 15.

When valve body 34 has completed its leftward movement, so that the left end of the piston 38 abuts the end of chamber 16, as seen in FIGURE 2, reservoir 90 is enlarged to its maximum volume. In this position, maximum flow communication is established from reservoir 90 and recess 35 through passages 36, annular chamber 32 and passages 31, 20, 19 and 18 to hydraulic line 11. This accommodates downward movement of the press ram and die pad during the work stroke. As the ram and die pad descend, maximum flow of the fluid from the cylinder to the accumulator continues through line 13, passage 48, relief valve 46, check valve 80, reservoir 90, passage 37, recess 35, passage 36, chamber 32, passages 31, 20, 19, and 18 and line 11 (see FIGURE 2).

Maximum flow accommodates steady downward movement of piston 15 within cylinder 14 as the press stroke continues. When the press stroke has been completed, pressure within line 13 drops to substantially zero, and relief valve 46 returns to its initial at rest, partially open position. At this time, the press stroke is completed.

It is now necessary to elevate the piston 15 for the next press stroke. Check valve 80 closes against seat 36 to prevent accumulator-to-cylinder flow. Unitary reciprocable elements 38, 40 and 34 move to the right braking communication between radial passages 36 and valve body passage 20, thereby trapping a measure of buffer hydraulic fluid in the reservoir 90, in the axial recess 35 of movable valve body 34 and in the passage 22, as fluid under accumulator pressure flows from conduit 11 into chamber 16. Fluid thus entrapped within reservoir 90, axial recess 35 and passage 22 is under a pressure greater than the accumulator pressure, which greater pressure acts upon the face 96 of check valve 41 to hold the check valve closed as elements 38, 40 and 34 move rightward.

Thus, at this juncture, there will be no flow from line 11 to line 13, members 38, 40 and 34 being positioned between their extreme left and right positions and moving relatively slowly toward the right, as viewed in the figures. The fluid entrapped in chamber 90 between piston 38 and fixed sleeve 27 and also within recess 35 resists such movement according to the amount of fluid escaping therefrom through sleeve slot 25 of the bleed valve 24. The adjustment of handle 26 will axially posi-

tion bleed valve 24 with respect to bleed valve sleeve 23 and will therefore determine the time necessary before flow is effectuated between lines 11 and 13 and, accordingly, the amount of time delay following the press work stroke before the piston commences upward movement toward its extended position. This time delay accommodates ease of stripping the fabricated workpiece from the die elements.

Once the valve body 34 has moved rightward to an extent such that radial passages 36 are brought into communication with chamber 30a and passages 29 and 30, fluid entrapped in reservoir 90 and passages 35 and 22 will escape to line 13 by this route. Until then, the above described delay mechanism entirely prohibits escape of any fluid into piston conduit 13. After this condition has been obtained, valve body 34 moves swiftly with a snap action to its extreme rightward position causing body 34 to again seat against sleeve 27 at 92.

Once the entrapped fluid in reservoir 90 and passages 35 and 22 escapes through passage 30 to line 13, accumulator pressure acting upon face 98 of check valve 41 overcomes the resistance of spring 42, causing check valve 41 to open, as illustrated in FIGURE 3. Thereafter, hydraulic fluid freely flows at accumulator pressure through check valve 41, axial recess 35, radial passages 36, passages 30 and 48, line 13, into cylinder 14, to cause piston 15 to return to its extended position.

Thus, the present invention provides a hydraulic control system intermediate an accumulator and a press responsive piston, being of simplified construction and improved operation. A continuously open, variable discharge, relief valve (located on the cylinder side of the main valve body) is utilized in conjunction with a hydraulically floating combination delay and check valve assembly (which is hydraulically responsive) to provide a common flow path to and from the cylinder and permitting (through the relief valve) initial indirect flow between the cylinder and the accumulator through a progressively enlargable hydraulic fluid storage reservoir, so as to alleviate the shock load induced by the high initial cylinder pressure upon the hydraulic system and upon the die elements. The relief valve is preferably a unitary cartridge accommodating easy, unitary removal and replacement, thereby requiring essentially no special equipment or down time for the exchange. The variable capacity hydraulic fluid storage reservoir, in conjunction with the continuously open variable discharge relief valve, provides a graduated cushioning effect permitting smooth operation of the press mechanism during the working stroke. The floating combination delay and check valve also facilitates return flow from the accumulator to the cylinder by providing a progressively decreasing storage volume of trapped hydraulic fluid in the reservoir which is slowly discharged therefrom into the accumulator conduit for a controlled duration of time to delay return of the piston to its extended initial position, facilitating separation of the workpiece from the die elements. This operation prohibits entry of hydraulic fluid into the cylinder conduit during the delay action and, consequently, the piston remains in its fully retracted position during the delay for improved stripping of parts being fabricated.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a ram-type press wherein a die pad engages the work and is retracted upon the closing of the press ram, a hydraulic cylinder and piston reacting upon said die pad

to resist such movement and to return the die pad to its extended position after opening of the press ram, an accumulator tank of hydraulic fluid under relatively low pressure, hydraulic fluid flow and pressure transmitting connections between said tank and cylinder for supplying hydraulic fluid under tank pressure to the cylinder when the tank pressure exceeds that of the cylinder, and continuously open valve means disposed in said hydraulic connections and accommodating the flow of fluid from said cylinder so as to cushion the shock load of hydraulic fluid from said cylinder during closing of the press ram, said valve means comprises a continuously open relief valve having a stationary pervious portion and a movable portion thereof having hydraulic pressure responsive surfaces to cause said movable portion to move relative to said stationary portion in response to pressure differential to thereby permit increased fluid flow through said relief valve following closing of the press during the work stroke thereof.

2. A device as defined in claim 1 further including a selectively settable means for varying the degree of resistance afforded against said relative movement of said movable portion with respect to said stationary portion of said continuously open relief valve.

3. A valve mechanism for controlling the flow of hydraulic fluid between an accumulator and a cylinder contained pressure-actuated die pad piston cushion, comprising a main valve body interposed between said accumulator and said cylinder, fluid means connecting said main valve body to said accumulator and said cylinder, respectively, and pressure responsive delay and check combination valve means biased between extreme positions in said main valve body solely by differential fluid pressure exerted thereon so as to permit fluid flow to and from said cylinder through a common main flow passageway having a plurality of ingress and egress fluid passageways, to provide a time delay between the completion of the piston work stroke and return of the piston to its extended position to its extended position thereafter.

4. A device as defined in claim 3 wherein said delay and check combination valve means includes reciprocating body means and spring biased check means carried by and normally unitarily movable with said body means so as to prevent cylinder to accumulator flow through said check means and to accommodate accumulator to cylinder flow therethrough when said check means is acted upon solely by fluid under accumulator pressure and by said spring bias.

5. A device as defined in claim 3 further including a stationary sleeve means interposed between said main valve body and said delay and check valve means accommodating reciprocal movement thereof, providing a variable volume hydraulic fluid reservoir therebetween and having fluid ingress and egress means such that fluid under piston pressure will cause said variable volume reservoir to progressively enlarge thereby alleviating shock load induced by cylinder pressure initiated by the commencement of the press work stroke and capable of entrapping fluid in said variable volume reservoir at the completion of said work stroke and discharging said entrapped fluid at a slow controlled rate to progressively decrease the volume of said chamber to thereby delay return of said piston to its extended position.

6. A device as defined in claim 5 having selectively settable means for varying the rate of discharge of said entrapped fluid.

7. In a hydraulic system of the type described for controlling the movement of a die or like press including piston-containing cylinder means, accumulator means and main valve body means interconnected by appropriate fluid conveying passageways, the improvement comprising continuously open relief valve means within said main valve body means enabling controlled initial cylinder-to-

accumulator flow at the commencement of the press working stroke upon the piston to cushion against high initial pressure build-up and resulting shock loads upon die elements and upon the hydraulic system, said valve means comprising a fixed apertured sleeve and a movable portion guided by said sleeve and having a first extreme position wherein a portion of the apertures of said sleeve are uncovered and a second extreme position wherein the entire apertures are uncovered.

8. A valve mechanism for controlling the flow of hydraulic fluid between the accumulator and a press-actuator die pad cushion carried by a piston containing cylinder, comprising a main valve body interposed between said accumulator and said cylinder, fluid means connecting said main valve body to said accumulator and said cylinder, and pressure responsive combination delay and check valve means reciprocally biased between extreme positions, said delay and check valve means including means providing a variable volume cushioning reservoir for hydraulic fluid under accumulator pressure to thereby alleviate shock loads normally initiated at the commencement of the press work stroke, controlled reservoir discharge means for delaying return of the piston to its extended position following the press work stroke, means accommodating cylinder-to-accumulator hydraulic fluid flow during a latter interval of the press work stroke, and means accommodating accumulator-to-cylinder hydraulic fluid flow during an interval of the period wherein said piston is resuming its extended position.

9. A device as defined in claim 8 and further including pressure relief valve means situated within said main valve body on the inlet side of said delay and check valve means when fluid is flowing from the cylinder to the accumulator, said discharge means including a bleed valve and bleed passage located between said pressure relief valve means and said accumulator on the outlet side of said pressure relief valve means.

10. In a valve mechanism for controlling the flow of hydraulic fluid between an accumulator and a cylinder contained pressure-actuated die pad piston cushion, comprising a main valve body interposed between said accumulator and said cylinder, fluid means connecting said main valve body to said accumulator and said cylinder, the improvement comprising pressure responsive hydraulically delay-check combination valve means biased between extreme positions in said main valve body solely by differential fluid pressure exerted thereon so as to permit fluid flow to and from said cylinder through a common main flow passageway which has a plurality of ingress and egress fluid passageways and to cushion against excessive cylinder pressure loads and to provide a time delay between the completion of the piston work stroke and return of the piston to its extended position thereafter, and continuously open relief valve means disposed in said main valve body on the cylinder side thereof so as to cushion against excessively high pressure build-up by enabling a controlled initial discharge of hydraulic fluid from said cylinder through the continuously open relief valve means into the delay check combination valve means during closing and initial work movement of the press ram.

11. In a ram-type press, wherein a die pad engages the work and is retracted upon the closing of the press ram, having a hydraulic cylinder and piston reacting upon said die pad to resist such movement and to return the die pad to its extended position after opening of the press ram, an accumulator tank of hydraulic fluid under relatively low pressure, and hydraulic fluid flow and pressure transmitting connection means between said tank and cylinder for supplying hydraulic fluid under pressure to the cylinder when the tank pressure exceeds that of the cylinder and for supplying hydraulic fluid under cylinder pressure when the cylinder pressure exceeds the tank pressure, the improvement comprising a continuously open valve assembly means disposed in said hydraulic

connection means and accommodating the flow of fluid from said cylinder so as to cushion the shock load of hydraulic fluid from said cylinder during closing of the press ram, said continuously open valve assembly means comprising stationary means, means movable relative to said stationary means, said movable means being biased in said first extreme position to accommodate limited flow between the cylinder and accumulator, and means for creating a pressure differential on opposite sides of said movable means to move said movable means toward a second extreme position when the cylinder pressure exceeds the tank pressure, said stationary and movable means combining to provide continuously open fluid communication opening means having flow capacity varying with the position of said movable means.

12. The improvement as defined in claim 11 further including a check valve means within said hydraulic connection means intermediate said accumulator tank and said continuously open valve assembly means accommodating cylinder-to-accumulator flow while preventing accumulator-to-cylinder flow through said check valve means and said continuously open valve assembly means.

13. In a ram-type press having a hydraulic cylinder and piston, an accumulator, and fluid connection means between said cylinder and said accumulator, the improvement comprising a valve mechanism disposed within said fluid connecting means for accommodating cylinder-to-accumulator flow of hydraulic fluid and for controlling the flow of hydraulic fluid between the accumulator and the cylinder, said valve mechanism comprising in combination a pressure responsive delay valve means to provide a time delay between the completion of the piston work stroke and the return of the piston to its extended position thereafter and check valve means carried by and forming part of said delay valve means, said check valve means being movable between a normally closed position and at least one open position by pressure differential on

opposite sides thereof, said check valve means accommodating fluid flow from said cylinder across one said opposite side and to said cylinder across at least the other of said opposite side.

- 5 14. In a ram-type press wherein a die pad engages the work and is retracted upon the closing of the press ram, a hydraulic cylinder and piston reacting upon said die pad to resist such movement and to return the die pad to its extended position after opening of the press ram, an accumulator tank of hydraulic fluid under relatively low pressure, hydraulic fluid flow and pressure transmitting connections between said tank and said cylinder for supplying hydraulic fluid under tank pressure to the cylinder when the tank pressure exceeds that of the cylinder, 10 a continuously opened, unit relief valve disposed in said hydraulic connections and continuously accommodating flow of fluid from said cylinder so as to cushion the shock load of hydraulic fluid from said cylinder during closing of the press ram, and removable means positioning said 15 unit relief valve in said hydraulic connections and accommodating unitary removal and replacement of the unit relief valve therefrom with essentially no press down time.
